CARBURETOR

James F. Armstrong, Plainfield, N. J.

Application April 16, 1943, Serial No. 483,239

4 Claims. (Cl. 261—72)

(Granted under the act of March 3, 1883, as
amended April 30, 1928; 370 O. G. 757)

The invention described herein may be manufactured and used by or for the Government for governmental purposes, without the payment to me of any royalty thereon.

The present invention pertains to a novel carburetor which is especially useful for aviation engines although not particularly limited thereto.

One of the objects of the invention is to provide a carburetor whose operation is not materially affected by its angular position, whether the carburetor be displaced 90 degrees or even completely inverted. This object is realized by providing a bowl with opposed diaphragms acting upon a fuel supply valve to control the fuel level therein and by positioning the discharge orifice in the volumetric center of the fuel bowl. In positions other than upright, the weights of the individual diaphragm operating mechanisms are equal and opposite so that they do not affect the valve when the carburetor is tilted.

The invention also includes a novel accelerating system which, when required, draws a proper charge of fuel from the line but independently of the bowl inlet and forces it under pressure into the manifold pipe. This charge is sufficient until the motor picks up speed and draws the required amount of fuel from the bowl.

Another characteristic of the invention is that all of the air that enters the fuel bowl passes into the main fuel passage and to the intake manifold pipe, thereby contributing to the improved operation of the device as described more fully hereinafter.

The invention is fully disclosed by way of example in the following description and in the accompanying drawings in which:

Figure 1 is a cross section of the carburetor on the line 1—1 of Figure 2;

Figure 2 is a side elevation;

Figure 3 is a section on the line 3—3 of Figure 1;

Figure 4 is a plan view, partly in section and Figures 5 and 6 are sections on the lines 5—5 and 6—6 of Figure 2.

Reference to these views will now be made by use of like characters which are employed to designate corresponding parts throughout.

The body of the carburetor includes the usual manifold pipe 1 and a receptacle 2 constituting the bowl or liquid chamber. This chamber and the parts associated therewith also perform the function of the usual float chamber, as will presently appear, so that no separate float chamber is used. The sides 3 of the body are enlarged and substantially circular for the attachment of bolted plates 4 and 5 to hold a pair of diaphragms, as will presently be described. One of the inter-

mediate sides 6 of the body 3 is integral with the main casting, and the opposite side 7 is an inserted sheet metal member.

Within the pipe 1 is inserted a Venturi member 8 with a hollow cross bar or tube 9 across the narrowest portion of the throat. A member 10 extends from the pipe 1 to the plate 7 and is suitably channeled to provide a vent passage 11 for the bowl. The member 10 is extended to the center of the bowl by means of an inserted tube 12. A second tube 13 is also inserted in the member 10 concentrically within the tube 12 to constitute the main fuel passage. A ring 14 is inserted in the free end of the tube 13 and is formed with an apertured flange 15 bridging the space between the tubes 12 and 13. The member 14 constitutes the main fuel orifice and the apertures 15 in the flange are the fuel bowl vent holes.

20 The top of the bowl receives a fuel inlet 16 fitting formed at its lower end with a valve seat 17. A valve stem or rod 18 passes through the seat and carries a valve plug or head 19 held on the seat by a spring 20 which bears against a 25 perforated retainer plate 21 secured in the fitting 16.

20 Diaphragms 22 and 23 are held against the portions 3 by the bolted cover plates 4 and 5 respectively. The intermediate portion of each diaphragm is held between two rigid disks 24 in the usual manner. The stem 25 is threaded through washers 26 at the center of each diaphragm and is secured by a cap nut 27. The plate 4 is bulged outwardly at 28 to accommodate the nut 27. Opposite the cap nut on the diaphragm adjacent to the plate 5, the plate is formed with a tapped nipple 29 into which is inserted a fuel level adjusting screw 30. A spring 31 is positioned between the screw and adjacent washers 26. Adjustment of the screw regulates the spring tension on the adjacent diaphragm and on the valve 19 through the connecting linkage which will now be described.

From an intermediate point of each stem 25 a link 32 extends to the bottom of the bowl and is pivotally attached to both parts at 33 and 34. From the inner end of each stem a link 35 extends to the top of the bowl and is pivotally attached to both parts at 36 and 37, the pivot points 37 being disposed at opposite sides of the valve 19 as shown in Figure 1. The upper end of each link 35 is formed with an inwardly extending finger 38 slidably received in a socket member 39 carried on the lower end of the valve stem 18. This mechanism transmits movement of the diaphragms to the valve stem 18. The tube 9 is formed with ports 40 for discharge of fuel.

In the operation of the device as thus far described, it may be assumed that the screw 30 has been adjusted to maintain the fuel level in the bowl at the line A with the engine stopped. The level may vary slightly with the density of the fuel and with the fuel pressure on the valve 19, the latter being maintained substantially constant by such means as, for example, a diaphragm-controlled relief valve in the fuel pump. The passage of air through the venturi 8 will cause depression at the ports 40 and in the member 14.

The depression pressure communicated to the bowl from the orifice 40 in the Venturi system and, acting on the diaphragms 22, 23, draws them towards each other and lifts the valve head 19 from its seat to permit fuel to enter the bowl. In the construction shown, the fuel lift need not exceed $\frac{1}{16}$ of an inch to bring the level to the orifice at the member 14. The cylinder suction and the Venturi action will draw fuel through the tube 13, bar 9 and ports or jets 40 which discharge into the air stream.

The small apertures 15' in the member 14 thus provide a vent therefor. Obviously, in order to utilize fully the available metering depression, the apertures 15' in member 15 must be of a small area in relation to the main orifice in member 14. The suction through the main orifice in the member 14 results in opening the valve 19 and the fuel level will rise from its level at A until it reaches the orifice and is drawn therethrough into the tube 13 and discharged through the ports 40 into the air stream in the venturi 8. As long as a portion of the orifice in the member 14 is open to the fuel bowl the valve 19 will remain open and fuel will be admitted to the bowl. If fuel is admitted through the valve 19 faster than it is discharged through the orifice, the fuel level will rise until the orifice is completely covered, at which time the valve 19 will close since the fuel bowl is no longer in communication with the suction. Inasmuch as there are a plurality of small apertures 15' spaced from each other near the periphery of the flange 15, it will be apparent that one or more of the apertures will be above the fuel level even when it completely covers the main orifice, and the fuel bowl will be vented through the passage 11. Since both the air vent and the fuel orifice are located in the volumetric center of the fuel bowl, the carburetor will function as described above regardless of the position of the carburetor. A portion of the depression is lost for venting the fuel bowl at the apertured member 15. In practice this loss need not exceed 15% to 20% to provide the fuel bowl with a suitable vent. A constant mixture ratio curve at open throttle with a manifold depression from one-half to two inches of mercury is readily obtainable.

The location of the orifice 14 and the construction of the diaphragm mechanisms are of primary importance. The orifice, it will be seen, is in the volumetric center of the bowl. The construction of the diaphragm mechanisms is such that the individual mechanisms operate oppositely on the fuel valve if the carburetor is tilted from the position shown in Figure 3. For example, if the carburetor is tilted to the right, the weight of the right hand mechanism will tend to draw the valve stem 18 downward, while the weight of the left hand mechanism will tend to move the valve stem upward. Thus, the relative position of the valve 19 is not affected by the

position of the carburetor, even if it be rotated 90° or entirely inverted. Similarly, the delivery of fuel to the member 14 is not affected because of the location of the latter in the volumetric center of the bowl. For the same reason, there is no egress of fuel from the bowl, in any position, without Venturi depression in passage 13. The importance of these properties in aviation will readily be appreciated.

10 The idling system comprises a tube or jet 41 mounted within the bar 9, and extending to a passage 42 formed in the wall of the pipe 1 adjacent to the mixing chamber 43. In the chamber is rotatably mounted a throttle valve shaft 44 carrying a butterfly throttle valve 45. Ports 46 and 47 are drilled in the wall to connect the passage 42 with the chamber 43 and are preferably located respectively above and below the throttle valve in closed position. The intake 15 end of the tube 41 is closed at 48 and the side walls are perforated at 49, thereby reducing the intake area to requirements and causing the tube to function as a metering jet. Also, a mass of liquid fuel in the tube 41 is not likely to cover 20 all the perforations, so that the air cannot be completely choked off.

25 The upper end of the passage 42 communicates at 50 with the pipe 1 on the air intake side of the venturi, and the effective area of the port 30 50 is regulated by an adjusting screw 51. This 30 constitutes a bleeder or vent for the idling system, to regulate the amount of fuel drawn into the mixing chamber 43 by the idling engine. The main discharge jets 40 also act as air bleeds 35 on the idling system, while the Venturi depression is less than the main fuel passage depression.

40 At open throttle, some of the air entering the port 50 passes through the tube 41 and bleeds 45 the main fuel discharge ports 40 to a very slight degree. In order to supply sufficient fuel to idle the engine properly at a slightly greater speed than as low idle, the port 46 is so positioned that it becomes effective when the throttle valve is opened slightly. In this manner the depression 50 in the idle passage is increased sufficiently to furnish the desired fuel richness at small throttle opening.

55 The economizer system comprises a diaphragm 52 clamped to the bottom of the bowl by a plate 53 and having one side exposed to the bowl through a port 54. The opposite side of the diaphragm is exposed to the mixing chamber 43 through a suitably shaped passage 55. A 55 suitably supported bracket 56 pivotally supports a valve crank lever 57 provided on one arm with a pin 58 adapted under certain conditions to enter the member 14 and restrict the orifice. The other arm of the lever 57 is engaged by a rod 59 mounted on the diaphragm 52. A spring 59 between the diaphragm and the plate 53 tends to remove the pin 58 from the orifice against the action of a tension spring 60 joining the lever 57 to an opposite point on the bracket 56.

65 When the pressure in the mixing chamber between the throttle valve 45 and the engine valves exceeds the pressure in the bowl by four or five inches of mercury, the diaphragm 52 compresses the spring 59 and the tension spring 60 draws the pin 58 into the orifice 14 as shown in dotted lines in Figure 1. This obstruction in the main fuel orifice thins the fuel mixture to the desired degree for maximum economy in this condition of operation. When the mixing chamber pressure increases relatively to the bowl pressure, the

spring 58 overcomes the spring 60, and the pin 68 is withdrawn from the orifice to enrich the mixture for the maximum power output from the engine under these conditions.

The acceleration system is supplied with fuel through a fitting 61 mounted in a suitably formed plate 62 attached to a side of the pipe 1. The fitting is intended to be connected directly to the fuel supply pump or line without interfering with the bowl supply fitting 16. Between the plate 62 and the side of the pipe 1 is formed a chamber 63 in which is clamped a diaphragm 64. A passage 65 connects the fitting 61 with the inner side of the diaphragm. A check valve 66 is held against the outlet end of the fitting by a light spring 67.

Outside the pipe 1, the throttle valve shaft 44 carries an actuating lever 68 adapted to be linked to the acceleration pedal. The opposite end of the throttle shaft carries an arm 69 to which is pivotally attached a link 70. To the link is pivotally attached a lever 71 terminating in a fork 72 disposed adjacent to the plate 62. The fork carries a pin 73 pivoted in lugs 74 extending from the plate. A rod 75 secured to the center of the diaphragm 64 is adapted to slide in the plate 62 and towards a point on lever 71 spaced somewhat from the pin 73. A spring 76 between the diaphragm and the plate tends to withdraw the rod 75 from the lever.

The side wall of the pipe 1 and the plate 62 form a lower diaphragm chamber 77 in which is clamped a diaphragm 78. A fitting 18 mounted in the pipe wall adjacent to the diaphragm 78 provides a valve seat 80 opening into the mixing chamber 63 below the throttle valve. To the diaphragm 78 is clamped a channelled valve stem 81 having a head 82 normally seated on the valve seat 80 by a spring 83 at the opposite side of the diaphragm. Channels 84 and 85 connect the divisions of the chamber 63 respectively to the divisions of the chamber 77. In the operation of this portion of the apparatus, the fuel entering the fitting 61 has sufficient pressure to open the check valve 66 against the spring 67. The diaphragm 64 is thus moved sufficiently to bring the rod 75 against the lever 71. The fuel pressure is not normally sufficient, however, to overcome the spring 83 which holds the valve head 82 on its seat 80.

When the throttle valve is opened, the members 68 and 78 operate to swing the lever 71 and move the rod 75 and thus cause the diaphragm 64 to exert pressure on the fuel in the pressure side of the chamber 63. The check valve 66 closes under this pressure and the fuel is trapped. The increased pressure on the trapped fuel moves the diaphragm 78 against the spring 83, whereby the valve 82 is opened. This operation releases the necessary amount of fuel into the engine to cover the lag between the starting of the air flow and the starting of the fuel flow when the air flow through the venturi is suddenly increased.

The low pressure sides of the chambers 63 and 77 are vented by a passage 86 formed through the plate 62 and sidewall of the pipe 1 and extending to the interior of the pipe, as shown in Figure 5. Similarly, the enclosed space between each of the diaphragms 22, 23 and the adjacent cover plate is vented by a passage 87 extending from the space through said plate and the sidewall of the pipe 1 to the interior of the pipe, as shown in Figure 4.

Although a specific embodiment of the invention has been illustrated and described, it will be understood that various alterations in the details of construction may be made without departing from the scope of the invention as indicated by the appended claims.

What I claim is:

1. In a carburetor having a fuel bowl, an air pipe and a throttle valve in said air pipe, a fuel discharge tube extending from said pipe into said fuel bowl and having an entrance located substantially at the volumetric center thereof, a movable valve for admitting fuel into said bowl, operating means for said valve arranged to maintain fuel in said bowl substantially at the level of the volumetric center thereof when said throttle valve is open regardless of the angular position of the carburetor, a sleeve surrounding said fuel discharge tube and forming therewith an annular chamber, and a cap at the outer end of said sleeve substantially at the volumetric center of said bowl, said cap having a plurality of vent openings therein establishing communication between said annular chamber and said bowl to vent the latter.

2. In a carburetor having an air pipe and a bowl, a fuel discharge tube communicating with said pipe and extending into said bowl and terminating substantially at the volumetric center of said bowl, a sleeve concentric with and surrounding said tube and cooperating therewith to form an annular chamber therebetween, said chamber having one end communicating with said pipe, and a cap covering the outer ends of said tube and said sleeve, said cap having a central opening establishing communication between said tube and said bowl for the passage of fuel and a plurality of small openings establishing communication between said annular chamber and said bowl to vent the latter.

3. In a carburetor having a fuel bowl, an air pipe and a throttle valve in said air pipe, a fuel discharge tube extending from said pipe into said fuel bowl and having an entrance located substantially at the volumetric center thereof, a movable valve for admitting fuel into said bowl, operating means for said valve arranged to maintain fuel in said bowl substantially at the level of the volumetric center thereof when said throttle valve is open regardless of the angular position of the carburetor, and a series of relatively small vent passages arranged concentrically with said fuel discharge tube and opening into said bowl at points spaced radially outwardly from said tube.

4. In a carburetor having a fuel bowl, an air pipe and a throttle valve in said air pipe, a fuel discharge tube extending from said pipe into said fuel bowl and having an entrance located substantially at the volumetric center thereof, a movable valve for admitting fuel into said bowl, operating means for said valve arranged to maintain fuel in said bowl substantially at the level of the volumetric center thereof when said throttle valve is open regardless of the angular position of the carburetor, and a series of relatively small vent passages opening into said bowl at points spaced circumferentially about and radially from said entrance of said discharge tube and in fixed relation thereto, so that one of said vent passages is effective in any angular position of the carburetor.

JAMES F. ARMSTRONG.
